SIGNAL FOR RETAIL STORE CUSTOMER SERVICE
AND THE LIKE

Saul Leibow, 90 Massapoag Ave., Sharon, Mass.

Filed June 26, 1963, Ser. No. 75,521

Term of patent 3½ years

(Cl. D72—1)

FIG. 2

FIG. 1 is a front perspective view of a signal for retail store customer service and the like, showing my new design; and

FIG. 2 is a rear perspective view thereof. The broken lines are shown for illustrative purposes.

I claim:

The ornamental design for a signal for retail store customer service and the like, as shown and described.
